Primary Examiner — Susan Moon Lee(74) *Attorney, Agent, or Firm* — Taylor English Duma LLP(57) **CLAIM**

We claim the ornamental design for an elevated pet bowl, as shown and described.

DESCRIPTION

FIG. 1 is a perspective view of an elevated pet bowl. FIG. 2 is a perspective view of the claimed design from below. FIG. 3 is an exploded view of the claimed design showing a removable bowl of the elevated pet bowl separated from a base of the elevated pet bowl.

FIG. 4 is a front elevation view of the claimed design.

FIG. 5 is a rear elevation view thereof.

FIG. 6 is a left-side elevation view thereof.

FIG. 7 is a right-side elevation view thereof.

FIG. 8 is a top plan view thereof; and,

FIG. 9 is a bottom plan view thereof.

The features depicted in broken line are not claimed. Other embodiments not presently claimed include broken lines in place of one or more solid lines; consequently, other embodiments not presently claimed include one or more elements standing on their own merit. The ornamental design is not limited to the scale shown herein.
